A. K. MALMQUIST

LUBRICATING MEANS

Filed March 18, 1925

Inventor

A. K. Malmquist

By Seymour & Bright

Attorneys

UNITED STATES PATENT OFFICE.

ADOLPH K. MALMQUIST, OF SOUTH BELLINGHAM, WASHINGTON, ASSIGNOR TO MALMQUIST MACHINE COMPANY, OF SOUTH BELLINGHAM, WASHINGTON.

LUBRICATING MEANS.

Application filed March 18, 1925, Serial No. 16,434, and in Canada March 21, 1924.

This invention relates to improvements in lubricating means and more particularly for the rotary valve of canning apparatus, one object of the invention being to provide a traveling lubricator to wipe and lubricate the outer bearing surface of rotary valve in canning apparatus.

A further object is to so construct the lubricator that the continuously revolving can cap feed lever of a canning apparatus may be utilized to carry said lubricator.

With these and other objects in view, the invention consists in certain novel features of construction and combinations of parts as hereininafter set forth and pointed out in the claims.

In the accompanying drawings;

Figure 1 is a view partly in section illustrating an application of my improvements, and

Figure 2 is an enlarged sectional view partly in elevation.

In my copending applications Serial Nos. 582,712 and 734,225, is shown and described, mechanism for sealing caps to cans, for feeding caps to the sealing chamber and for discharging sealed cans from the sealing,—the cap feeding and can discharging mechanism including a rotary valve and the cap feeding means also including a revolving lever for moving can caps from a source of supply to said valve. My present invention contemplates lubricating means for said valve, and in the present instance the cap feed lever carries lubricating means.

In Figure 1 of the drawing is shown a portion of a can sealing chamber 1, in which is located sealing mechanism, fragments of which are indicated at 2; a casing 3 for a valve 4 is located adjacent to and connected with the casing of the sealing chamber and between the valve and sealing chambers, a bushing 5 is provided for the valve, and a revolving feed lever is shown at 6 for feeding caps from a cap magazine 7,—all of which mechanism as thus generally described being shown and described in my copending applications hereinbefore identified. In the present instance, however, a bridge 7^a is provided, as shown in Figure 1, for guiding and supporting the caps as they pass from the valve 4 to the sealing

mechanism. It may be here stated that the lever 6 may also be utilized for ejecting sealed cans leaving the valve.

The can cap feeding and can ejecting lever 6 is carried and revolved by a shaft 8 to which power may be applied in any suitable manner. The lever 6 is provided with a frame 9 which includes a block or enlargement 10 having a recess 11. The block or enlargement 10 is embraced by the flanged portions 12—13 of a holder 14 having a vertical socket 15 forming a seat in which a felt wiper 16 is secured. The upper portion of the back wall of the socket or seat is provided with a groove 17 to receive lubricant to be fed to the felt wiper and the free vertical edge of the latter is provided with a groove 18 to prevent the wiper from becoming clogged. The holder 14 is provided with a central enlargement 19 and an elongated hole 20. A spring 21 seated in the recess 11 bears against the enlargement 19 and serves to press the holder and wiper forwardly,—the movements of the latter being limited by a pin or bolt 22 carried by the frame 9 and passing through the elongated hole 20.

The upper end of the shaft 8 is provided with a threaded nipple 23 to receive and support a lubricant well or receptacle 24 and the latter communicates with a horizontal pipe or duct 25 carried by the frame 9. This pipe or duct extends over the upper end of the wiper 16 and discharges at its free end at the upper end portion of the feed duct 18 in the free edge portion of the wiper. The pipe or duct 25 is also provided with a part 26 which discharges into the upper end of the lubricant duct or passageway 17 in rear of the rear edge of the wiper.

It will be seen that as the lever 6 revolves with the shaft 8, the wiper 16 of the lubricating device will wipe the outer bearing surface of the valve 4 and lubricate the same.

If desired, the upper and lower portions of the valve, above and below those portions engaged by the wiper, may be lubricated by separate lubricators 27, 28.

Various changes might be made in the details of construction of my invention without departing from the spirit thereof

or limiting its scope and hence I do not wish to restrict myself to the precise details herein set forth.

Having fully described my invention 5 what I claim as new and desire to secure by Letters-Patent, is:—

1. In apparatus of the character described, the combination with a valve, of a revoluble lubricator having a wiper, said lubricator being positioned to wipe and lubricate the outer bearing face of the valve during the rotation of said valve and the revolution of the lubricator.

2. The combination with a revoluble 15 frame, of a holder having sliding connection therewith, a wiper carried by said holder, and means for supplying lubricant to said wiper.

3. The combination with a revoluble 20 lever, and a frame carried thereby, of a holder having sliding connection with said frame, a wiper carried by said frame, a spring tending to press said holder outwardly, and means to supply lubricant to said wiper.

4. The combination with a rotatable 25 frame, of a flanged holder embracing a portion of said frame and movable thereon, a wiper carried by said holder, a spring tending to press said holder outwardly, and means to supply lubricant to said wiper.

5. The combination with a rotatable

frame, of a flanged holder embracing a portion of said frame and movable thereon, a wiper carried by said holder, a spring tending to press said holder outwardly, limiting 35 means for said holder and the wiper carried thereby, and means to supply lubricant to said wiper.

6. The combination of a revoluble frame, 40 a holder carried thereby and having a seat provided with a lubricant groove, a wiper in said seat in front of said groove, a lubricant well, and a duct communicating with said well and having a part communicating 45 with said lubricant groove.

7. The combination of a revoluble frame, 50 a holder carried thereby, a wiper carried by said holder, and having a groove in its free edge, a lubricant well, and a duct communicating with said lubricant well and extending over the upper end of said wiper, said duct having an opening to discharge into the groove in the free edge of the wiper.

8. The combination with a revoluble 55 shaft and a frame carried thereby, of a yielding holder carried by said frame, said holder having a seat, a wiper in said seat, a lubricant well carried by the shaft, and a duct communicating with said well and 60 adapted to conduct lubricant to said wiper.

In testimony whereof, I have signed this specification.

ADOLPH K. MALMQUIST.
